UNITED STATES PATENT OFFICE.

VINCENZO PELLEGRINO, OF RYE, NEW YORK.

COVER FOR CURATIVE MEDICINES.

Application filed June 22, 1925. Serial No. 38,658.

This invention relates to improvements in holders or containers for curative remedies for corns, or the like, and it is the principal object of the invention to provide a holder which can readily be attached to any part of the body afflicted with a corn, or other sores, to securely hold the corn plaster or remedy in place in order to let its curative properties work undisturbed.

Another object of the invention is the provision of a container or holder for a corn remedy of simple and inexpensive construction providing for the necessary ventilation.

A further object of the invention is the provision of a device of this character having the form of a capsule allowing an adjustment of its height, etc.

These and other objects and advantages will become more fully known as the description thereof proceeds and will then be more specifically defined in the appended claim.

In the accompanying drawing forming a material part of this disclosure:

Fig. 1 is a top plan view of a holder for a corn-plaster or other curative remedies.

Fig. 2 is a section on line 2-2 of Fig. 1.

Fig. 3 is a top plan view of a modified form of my device.

Fig. 4 is a side elevation of another modification of the same.

Fig. 5 shows in side elevation, a further modified form of my device, representing a capsule.

Fig. 6 is an enlarged detail view of the adjustable cap for the capsule, Figure 5.

The holder according to the present invention illustrated in Figures 1 and 2, comprises an elongated band 10 of suitable shape and material, as for instance rubber or rubberized fabric which has in its center a hollow boss or projection 11, into the hollow space of which a wad of cotton saturated with a corn curative remedy or plaster is placed. The band is attached to the part of the body afflicted with a corn, as for instance a toe, by means of the snap-button 12 attached at one end of the band and adapted to engage in the well known manner, a socket 13 at the opposite end of the body, or other suitable fastening means, such as hooks and eyes, etc., may be used.

In Figure 3, a band 14 is illustrated which has a plurality of openings 15 formed there-

in for ventilating etc. purposes, and similar openings 16 are formed in the central holding member 17 for the curative. Also this form is attached to the part of the body afflicted with a corn by means of a snap-button fastening 18 and 19 or by any other suitable securing means.

In the form of my invention illustrated in Figure 4, the band 20 has formed in its middle part simply an opening into which a wad of cotton 21, saturated with a remedy may be introduced and held therein by the reinforced and somewhat projecting inner margin 22 of the material forming the opening. Also in this form a snap fastening 23, or the like, may be used to fasten the device to the body part.

In the modification illustrated in Figures 5 and 6, the band 24 has inserted into its central opening, a socket 25 held in place by its lower flange 26 and a reinforcement 27.

A cap or cover 28 is hingedly attached to the socket as at 29, and has a substantially Z-shaped slit 30 formed in its side wall into which engages a pin 31 of an extension cap 32, or the like for allowing the introduction and holding of a smaller or larger wad of cotton saturated with the corn curative in the capsule.

It will be understood that I have shown in the drawing and described the preferred forms of my invention as examples only, and that my device is capable of many changes coming within the scope of the claim without departure from the spirit of the invention.

Having thus described my invention what I claim as new, and desire to secure by Letters Patent, is:

A holder for a corn remedy comprising a band having a centrally located opening formed therein, a socket in said opening for the reception of the corn remedy, a means for holding said socket to said band, a means for attaching said band to a part of the body, a cap hinged to said socket, said cap having a Z-slit formed therein, an auxiliary extension cap in said main cap, and a pin on said auxiliary cap entering said Z-slit and guided therein for holding said auxiliary cap to the main cap and for guiding the same in its relative positions.

In testimony whereof I have affixed my signature.

VINCENZO PELLEGRINO.
